UNITED STATES PATENT OFFICE.

LEWIS MILLER AND WILLIAM JUDSON GRIFFITH, OF GLENMARY, TENNESSEE.

RAILROAD-GATE.

1,386,581.

Specification of Letters Patent. Patented Aug. 2, 1921.

Application filed January 30, 1920. Serial No. 355,023.

To all whom it may concern:

Be it known that we, LEWIS MILLER and WILLIAM JUDSON GRIFFITH, citizens of the United States, residing at Glenmary, in the 5 county of Scott and State of Tennessee, have invented new and useful Improvements in Railroad-Gates, of which the following is a specification.

This invention relates to safety appliances, 10 such as signaling means and barriers for railway crossings or like dangerous places, the purpose being to provide novel actuating means for the safety appliances which are adapted to be electrically operated from any 15 point or points in the length of the track from either approach and at required distance from the crossing or like place to be safeguarded.

The foregoing and other objects which 20 will appear as the nature of the invention is better understood may be accomplished by a simple construction and combination of operative devices such as is illustrated by the drawings, it being understood, however, that 25 the nature of the invention is such as to render the same susceptible to modifications which fall within the scope of what is claimed.

In the drawings:

30 Figure 1 is a plan view of a railway crossing provided with the improved safety appliance, the electric elements including circuits, etc., being shown diagrammatically and the gate being in open position.

35 Fig. 2 is a similar view showing the arrangement of parts when the gate is closed and locked in accordance with this invention.

While our improvement is adaptable to any number of tracks we have in the accompanying drawings illustrated a single track which is broadly indicated by the numeral 10. The rails 11 and 12 of the track are insulated from each other as indicated by the numerals 13, at points approximately four 40 hundred feet to each side of the crossing 14. The crossing is provided with the usual safety gates 15 placed on opposite sides of the track, only one of such gates being shown in the drawings. The gates 15 may be operated either electrically or manually and as 45 disclosed by the drawing the gate 15 is provided on its inner end with a socket 16 designed to be engaged by a bolt member 17 when the gate is in closed position as illustrated in Fig. 2 of the drawing.

Electrically operated signals 18 are placed on opposite sides of the crossing 14, only one signal, however, being illustrated by the drawings.

On one side of the track 10 adjacent to 60 the insulated ends of the rails 11 are track batteries 19 to which are connected wires 20 and 21 leading from the rails 11 and 12 respectively of the track. On one side of the rail 12 are a plurality of relay magnets 22 65 which are wired, as at 23, and 24 to the energized rails 11 and 12. The number of relay magnets 22 correspond to the insulated sections of the energized rails of the track 10.

The numeral 24' designates the signal relay battery and 25 and 26 the circuit wires therefrom. On the wire 25 are the armatures 27 for the relay magnets 22.

The wires 25 and 26 of the common circuit are connected at the ends thereof to a relay 75 magnet 28 disposed opposite the signal 18. The armature for the magnet 28 is indicated by the numeral 29, and the wires leading to the signal are indicated by the numerals 30 and 31 respectively, and to the wire 31 the 80 armature 29 is connected.

The lock circuit which actuates the locking bolt 17 includes a battery 32 having wires 33 and 34 leading therefrom. The wire 34 is coiled around the magnets 35 of the lock 85 solenoid, and the armature 36 for the said solenoid is connected to the bolt 17. The wire 33 of the lock circuit has at the end thereof a relay armature 29' disposed adjacent to a relay 40 that is arranged opposite 90 one of the relay armatures 27. One of the branches of the wire 25, indicated for distinction by the numeral 41 is provided with contact elements for the relays 22, the said contact elements being indicated by the numerals 42, and from one of these branch wires extends the wire that is connected to the relay 28.

It will be apparent that the common circuit is closed when no train is in the blocks 100 on the opposite sides of the crossing 14 and that the same is opened when the train is in the block in which the crossing 14 is situated. When the train is in this block its relay 22 will be deenergized and the common circuit 105 is broken which closes the locking circuit. This energizes the magnet lock solenoid, causing the armature 36 to move the bolt 17 into the socket 16 of the gate 15 and locking the gate when the latter is in closed posi- 110

tion. It is to be understood that the locking mechanism can be of any form which locks when the current is in and opens when the circuit is broken. It will be also understood that the bolt 17 is in unlocking position when the train is in the block and that as the train approaches the block and remains therein the signal 18 will be brought to danger position.

10 Having thus described the invention, what is claimed as new, is:—

1. In combination with a railway track and crossing, said track having its rails on the opposite sides of the crossing insulated from each other and electrically energized, relay magnets connected to said energized rails, a common circuit including a battery having relay armatures for said relay magnets, contact elements for the armatures in said common circuit, said common circuit having therein an additional relay magnet, a signal in a normally open circuit, an armature in said circuit disposed opposite the last mentioned magnet and a contact in said circuit for said armature, a gate at the crossing, a lock circuit including a battery, a solenoid and a movable armature therefor designed when said circuit is closed to engage with the gate to lock said gate in closed position, and an armature in said lock circuit disposed adjacent to one of the armatures

for the energized track relay magnets, all as and for the purpose set forth.

2. In a device of the class described, in combination with a railway track and crossing, said track having its rails on the opposite sides of the crossing insulated from each other and electrically energized, relay magnets connected to said energized rails, a common circuit including a battery having 35 relay armatures for said relay magnets, contact elements for the armatures in said common circuit, a second relay deenergized when the track relay is deenergized, a signal controlled by the second relay, a gate at the 40 crossing, lock receiving means carried by the gate, a lock circuit including a relay armature disposed adjacent to a relay opposite one of the primary relay armatures, a battery, a solenoid having a movable armature 45 therefor, and a locking bolt slidably mounted between the magnets of the solenoid having one end thereof adjacent to the movable armature and adapted to be moved longitudinally by said armature when the lock 50 circuit is energized and engage the lock receiving means of the gate and lock the same in its horizontal closed position.

55 In testimony whereof we affix our signatures.

LEWIS MILLER.

WILLIAM JUDSON GRIFFITH.
